CURL HOLDER

Ruth N. Palitti, San Francisco, Calif.

Application September 4, 1951, Serial No. 244,903

4 Claims. (Cl. 132—43)

1

This invention relates to hair curling and more particularly to a holder for retaining a hair curl in its original form, and to a method of curling hair with such curl holder.

Summarizing the invention, the curl holder comprises a sleeve of flexible material having at one end thereof a flexible band. Preferably, the sleeve is made of hair net material and the band is provided with means enabling it to be adjusted as to size. A finger of the user is adapted to be inserted into the sleeve which is of a diameter sufficient to permit ready insertion of the finger; and the sleeve has an outer end portion opposite to the band end adapted to extend or project beyond the tip of the finger.

In employing the curl holder, the finger is inserted into the sleeve through the band end, the finger with the sleeve thereover is held adjacent the scalp, and a curl is formed around the sleeve over the finger. After formation of the curl, the band is pulled to turn a portion of the sleeve adjacent the band inside out over the curl and over the top of the finger and there released, permitting the band to grip around the root end of the curl. The extending portion of the sleeve is left free or loose to be pulled to any desired degree to tighten the curl.

The invention has as its objects, among others, the provision of an improved, simple and economical hair curl holder and hair curling method which do not require the use of pins, will form and hold the curl without slippage or spreading, which can be employed on wet, damp or even dry hair, which results in firm embracing of the curl to set the same, and which can form a relatively large size or tiny curl. Other objects will become apparent from a perusal of the following description of the invention.

Referring to the drawings:

Fig. 1 is an isometric view of the curl holder device with a finger inserted therein;

Fig. 2 is a similar view, partially schematic, showing one stage of the method embodying employment of the device;

Fig. 3 is a view similar to Fig. 2 illustrating a further stage of such method;

Fig. 4 is a more or less schematic cross-sectional view of the device in a curl holding position with a hair curl to be set embraced thereby;

Fig. 5 is an elevational view of the device in final curl holding position;

Fig. 6 is a fragmentary isometric view of the band end of a modified form of the device.

The preferred curl holder, as illustrated in Fig. 1, comprises a sleeve 2 of flexible material which

is provided adjacent one end with an elastic band 3 of rubber or any other suitable stretchable material, which thus serves the purpose of a garter ring. Sleeve 2 is secured to band 3 by any suitable means such as stitching or by a hem. Adjacent the band end, the sleeve is provided with an opening 4 into which a finger may be inserted; and preferably the opposite or outer end of the sleeve is also open at 5, although such outer end need not be open but may be closed if so desired.

Any suitable flexible material may be employed for the sleeve such as thin rubber, paper, or cloth fabric. However, inasmuch as the device is particularly adapted for the setting or form holding of curls in hair to which the usual type of lotions may be applied, the sleeve is preferably formed of open mesh hair net material as this allows the curl to dry readily. Furthermore, such open mesh hair net material will not stain from the use of the usual hair lotions; and it obviates matting of the hair.

In employing the curl holder, it is generally desirable to insert an index finger 6 through the band end; and the sleeve is of a diameter to enable free insertion of the largest size index finger generally encountered. The finger is generally inserted so that the band end of the sleeve is past the second knuckle; and the sleeve is of such length, for a purpose to be subsequently described, to provide an outer end portion thereof, indicated by the distance X in the drawings, to project or extend free or loose beyond the tip of supporting finger 6.

If band 3 is sufficiently elastic, it may be non-adjustable as to size as the great elastic character thereof will serve the purpose of gripping the root end of the curl in a manner to be explained. However, it is preferred that the size of the band be adjustable. For this purpose, in the preferred modification, band 3 terminates in two projecting end portions 7 which pass through a loop or ring member 8 which frictionally engages end portions 7. Loop member 8 may be of elastic material or of plastic, or any other suitable material. By pulling either end portion 7 through loop 8, it is apparent that the effective size of band 3 may be changed to adjust the grip, independently of the grip obtained by the elastic character of the band.

With reference to Figs. 2 and 3 which illustrate the method of employing the device, after finger 6 on one hand is inserted into the sleeve to support the same in the manner pointed out above, the finger with the sleeve supported thereon is held closely adjacent scalp 9 at a position where

a curl 11 is to be formed. If the person is making her own curl, she may wind the hair with her other hand around the sleeve and over finger 6 on which the sleeve is supported. After curl 11 has been formed, it may be held temporarily by another finger 12 on the hand of sleeve supporting finger 6. In the position of Fig. 2, it will be noted that the root end 13 of the curl is adjacent band 3 and to the right of such band with reference to the position of Fig. 2.

As the next stage in the method, band 3 is grasped at one side by the other hand at a position remote from the scalp, as indicated by reference character A; the opposite side of the band, indicated by reference character B, abutting root end 13 of the curl. Band 3 is stretched by pulling at A; and such portion A of the band and the portion of the sleeve adjacent thereto is turned inside out over the tip of finger 6, as indicated by the curved direction arrow line 14. In performing this operation, band 3 is not pulled over outer end 5 of the sleeve, but is pulled over an intermediate part of the sleeve so that the projecting portion represented by X will extend loose or free beyond the band. After the band is pulled over the tip of finger 6, the band is released and such finger is removed. Release of the band causes it automatically to encircle root end 13 of the curl and the loose or free projecting end portion X of the sleeve to hold the loose end of the sleeve against the root end of the curl.

Fig. 4 illustrates what occurs as a result of the above described operation after release of the band and removal of sleeve supporting finger 6. It will be noted that band 3 completely encircles root end 13 of the curl and the loose end portion X of the sleeve. In this position, the loose or projecting end portion X of the sleeve is pulled to tighten the portion of the sleeve enclosing the curl, and consequently the curl. Also, by pulling either of projecting end portions 7 of band 3, the band may be tightened to insure a tight grip of the band around the root end of the curl in a manner indicated by Fig. 5:

Thus, the curl is held fast in the net; and the net which has been turned inside out adjacent the inner end portion thereof is held fast by the band. The device may be kept on the hair until the curl has been set for a time according to the taste of the user. When it is desired to remove the device to free the set curl, the sleeve may be upturned away from the scalp, thus exposing the gripping or circle portion 15 of the band. Such circle portion of the band is pulled downwardly away from the root end 13 of the curl, thus unrolling the curl and freeing it from the curl holder. The device may be used over again.

In connection with the use of the device, it is to be understood that a plurality of the same may be employed on the scalp at one time to form as many curls as are desired by the individual. The device may be used with any type of hair which may have been wetted or is merely damp, or even with dry hair. Since it does not embody any pins, there is nothing to cause inconvenience to the user while sleeping.

The described modification with the two projecting end portions 7 on band 3 is preferred, as this permits the band to be adjusted by pulling either one of such portions. However, only one projecting portion need be employed to provide such adjustment as indicated in Fig. 6 wherein one end of elastic band 16 on flexible sleeve 17 is provided with a loop portion 18 through which the opposite end of the band is inserted to provide projecting end portion 19 which is frictionally gripped by loop 18. Band 16 may be adjusted as to size by pulling end portion 19. As previously mentioned, the above described adjustment of the band need not be provided as an elastic band of proper size and sufficient elasticity will provide the grip at the root end of the curl and enable the described manipulation. However, the adjustable feature of the band is preferred because it makes for more ready manipulation.

I claim:

1. A holder for an individual curl upon which said curl is adapted to be formed while a normal finger is inserted in said holder comprising a relatively narrow tubular sleeve of flexible open mesh material having a width to permit the insertion of said finger, the length of said sleeve being at least two times its width, whereby its outer end portion is adapted to extend beyond the tip of said finger, and an elastic band adjacent the inner end of said sleeve enabling an inner end portion of said sleeve to be turned inside out with the band encircling the root end of the curl.

2. A holder for an individual curl upon which said curl is adapted to be formed while a normal finger is inserted in said holder comprising a relatively narrow tubular sleeve of flexible open mesh material having a width to permit the insertion of said finger, the length of said sleeve being at least two times its width whereby its outer end portion is adapted to extend beyond the tip of said finger, an elastic band adjacent the inner end of said sleeve enabling an inner end portion of said sleeve to be turned inside out with the band encircling the root end of the curl, said band having a projecting end portion, and a loop member through which said end portion extends whereby the band may be tightened by pulling said end portion.

3. The holder of claim 1, in which said flexible material is hair net material.

4. The holder of claim 2, in which said flexible material is hair net material.

RUTH N. PALITTI.
